BODY BRUSH OR THE LIKE

Joseph Vallis, 448 Spadina Road, Toronto,
Ontario, Canada

Filed Aug. 29, 1960, Ser. No. 61,916

Term of patent 14 years

(Cl. D9—2)

Fig. 1.

Fig. 2.

Fig. 3.

Fig. 1 is a side elevational view of a body brush or the like, showing my new design;

Fig. 2 is an end elevational view thereof; and

Fig. 3 is a top plan view thereof.

The dominant features of my design reside in the portions shown in full lines.

The undisclosed side is a mirror image of the side shown and the end not shown is substantially plain as indicated in Figs. 1 and 3.

I claim:

The ornamental design for a body brush or the like, as shown and described.
